UNITED STATES PATENT OFFICE.

EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO.

HOLDER FOR MANIFOLDING BOOKS.

Application filed April 7, 1923. Serial No. 630,578.

This invention relates to an improvement in holders for manifolding books and with respect to its more specific features to resilient holders.

- 5 An object of the invention is to provide a holder for manifolding books, so constructed that the book will be firmly held, with the leaves in convenient recording position, until all of the leaves have been used.
- 10 Another object is to provide a holder in which the book is resiliently held, and which provides a supporting table for the book, to facilitate making of the record on the leaves.
- 15 Another object is to provide a holder, which will tightly grasp and hold the book regardless of the thickness thereof.
- 20 Another object is to provide a holder having a supporting table for the pad, in the form of a follower spring pressed toward the pad.
- 25 Another object is to provide a two-part holder, wherein the ends of the pad are clamped resiliently between the parts of the holder.
- 30 Another object is to provide a two-part holder for clamping the ends of the pad, wherein one of the parts is resilient and is held under tension by its engagement with the other to firmly clamp the pad.
- 35 Other objects of the invention will be in part obvious and will in part appear hereinafter.

The invention accordingly comprises an article of manufacture possessing the features, properties, and the relation of elements which will be exemplified in the article hereinafter described and the scope of the application of which will be indicated in the claims.

- 45 For a fuller understanding of the nature and objects of the invention reference should be had to the following detailed description taken in connection with the accompanying drawing, in which:
- 50 Figure 1 is a perspective view of an embodiment of the invention with a manifolding sales book in place,

Fig. 2 is a perspective view of a portion of the book,

Figs. 3, 5 and 7 are edge views of alternative forms of the invention, 55

Figs. 4, 6 and 8 are top plan views of Figs. 3, 5 and 7 respectively.

In the embodiment of the invention shown in Fig. 1, the improved holder is shown in 60 connection with a cover, consisting of a back 1, and a front 2, which are connected by a flexible hinge connection 3, as for instance leather. The holder proper is a two-part construction, consisting of an element in the 65 form of a plate 4, which is a follower, and on which the pad rests, and an element 5 which clamps the pad to the element 4. The element 5, which is resilient, in the present 70 instance, is provided at each end with an up-standing web 6 and 7, respectively, between which the pad 8 is received, and each web has at its top an overlying flange 9 and 10 respectively, the flange 9 being connected 75 with the web 6, while the flange 10 is connected with the web 7. In the present instance each flange 9 and 10 is provided at its ends with depending lugs 11, which engage the side edges of the pad 8, to prevent lateral movement thereof, with respect to 80 the follower, which is received between the webs 6 and 7, and which support the pad.

Resilient mechanism is arranged between the elements of the holder, and the said mechanism acts normally to move the elements away from each other, thereby to clamp the pad between said elements. In the present instance the resilient mechanism is in connection with the element 5, the said element being of resilient material, and bent 90 so that when it is engaged with the pad and follower, that is, the element 4, it will be held under tension. In the present construction, the element 5 is bent to provide three concave portions, separated by ribs 12 95 extending transversely of the element 5, and bearing against the element 4 when the elements are connected and clamped upon the pad. The improved holder is especially designed to hold that form of manifolding pad known as zigzag, wherein a series of record leaves is provided, connected end to end and folded so that they lie one upon the other. It is obvious, however, that the holder might be used with equal facility to hold any form 100 of manifolding pad. With the zigzag arrangement of manifolding pad, as many leaves may be disengaged as may be desired, 105

all connected together, by merely making traction on the uppermost leaf in the plane of the leaf, or substantially in the said plane. With other forms of manifolding pad, the 5 follower may be depressed at one end, by pressure on the pad, to permit disengagement of the free ends of the leaf or leaves from the flanges 9 or 10, as the case may be. The leaf 13 of transfer material is held by a 10 spring clip on the flange 10. This clip is in the form of a leaf which is hinged to the web 7, or to another leaf 14^a secured to the web 7, and it is normally spring pressed toward the flange 10, to tightly grip the end of 15 the transfer leaf between the said flange and the leaf 14. The transfer leaf may be disengaged, by swinging the leaf 14 upwardly. The element 5 may be connected to the back 1 of the cover in any suitable or desired 20 manner, as for instance by rivets indicated at 15.

In the embodiment of the invention shown in Figs. 3 and 4, the holder comprises an 25 element 16, which is a follower, and an element 17 of resilient material, held under tension by its engagement with the follower. This element 17, which is a plate, is bent in the same manner as the plate 5, and is provided at its ends with the vertical webs 30 18 and the overlying flanges 19, which engage the ends of the follower. The lugs 10 which limit the side movement of the pad are omitted, to facilitate the entrance of the 35 pad into the holder. In the embodiment of Fig. 1, the ends of the pad must be introduced beneath the flanges 9 and 10, the follower being depressed for this purpose. In Fig. 3, however, the pad may be slipped into the holder from the side. In Fig. 1, it 40 is engaged from the top.

In the alternate construction shown in Figs. 5 and 6, the element 20 which is the follower, is a plate, and the element 21 is also a plate, having the end webs 22 and the 45 overlying flanges 23—23^a against which the follower bears. The element 21 is bent in opposite directions on a transverse line at its center, and the angle formed by the bending is arranged upward, and bears 50 against the underside of the follower, pressing it against the flanges 23. When engaged with the follower, the element 21 is held under tension. With this construction the manifolding pad may be introduced 55 from the side, and in order to facilitate the introduction, the flange 23^a is cut away at each end, so that it is only a finger piece at the center of the web.

If desired, the two elements may be secured together as in the construction of 60 Figs. 7 and 8, wherein the follower 24 is secured to the element 25 which is a clamp, as indicated at 26, the connection being made in the present instance, by rivets. 65 The element or clamp 25, which is a plate,

has its central portion bowed up as shown at 27 to abut the plate 24, and it is the bowed up portion which is connected to the follower. The element 25 has the end webs 70 28 and the overlying flanges 29, and the flanges are provided with depending lugs 30 at their ends, which limit the lateral movement of the pad on the follower. The bow 27 is of such depth that it will tightly hold the follower against the flanges 29. 75

In order to insure the firm holding of the last few leaves of a manifolding pad, mechanism may be provided in connection with any of the holders shown for insuring a 80 tight grip at either or both ends of the holder. In Figs. 7 and 8, for instance, the overlying flanges 23 and 23^a have depressions 41 on their upper faces, which form spurs or lugs on the under faces of the flanges. The follower may have struck-up 85 spurs or lugs 42 at its ends, matching with the lugs 41, to tightly grip the leaves. In Figs. 10 and 11, the follower has spurs or lugs 43, which match with the openings 44 in one 90 of the flanges 34. The arrangement in Fig. 8 is especially adapted for the zigzag type of pad, since it will tightly grip both ends of the last few leaves. The construction of Fig. 11 is also adapted for this type, or for 95 any other type. In each of the constructions of Figs. 3, 5, 7, 9 and 10, a spring clip such as that shown in Fig. 1 may be provided to hold the transfer leaf, or any other suitable means may be used. In operation, to 100 introduce a pad, in the construction of Figs. 1 or 7, the ends of the follower are depressed, and the ends of the pad may be slipped into place one at a time or simultaneously. In the construction of Figs. 3, 5, 9 and 10, the pad may be inserted from the side, or from the 105 top as may be desired. The lugs 10 and 30 also prevent lateral movement of the follower, holding it in proper position in the holder, constituted by the follower and clamp. The improved holder is a two-part 110 holder, one of the parts being a follower, and a support for the pad, while the other is a clamp to clamp the pad to the follower, and one of the parts is resilient and held under tension by its engagement with the other. Either or both parts may furnish 115 the resiliency. The follower might be deformed and resilient, but it is preferable that the follower be plane to provide a support for the pad.

Since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the 130

generic and specific features of the invention herein described, and all statements of the scope of the invention, which, as a matter of language, might be said to fall 5 therebetween.

Having described my invention, what I claim as new and desire to secure by Letters Patent, is—

1. A holder for manifolding pad, comprising, in combination, a resilient plate, upturned webs at the ends of said resilient plate, and flanges carried by said webs, a rigid plate embraced between said resilient plate and said flanges, said resilient plate 10 being adapted to urge said rigid plate into engagement with said flanges and means for keeping said rigid plate and said resilient plate in lateral alignment. 15

2. A holder for manifolding pad, comprising, in combination, a resilient plate, upturned webs at the ends of said resilient plate and flanges carried by said webs, a rigid plate embraced between said resilient plate and said flanges, said resilient plate 25 being adapted to urge said rigid plate into engagement with said flanges and means for keeping said rigid plate and said resilient plate in lateral alignment, and a spring clamp carried by said web, engaging one of 30 said flanges for the retention of a transfer sheet.

3. A holder for manifolding pad, comprising, in combination, a resilient plate, upturned webs at the ends of said resilient 35 plate and flanges carried by said webs, a rigid plate embraced between said resilient plate and said flanges, said resilient plate

being adapted to urge said rigid plate into engagement with said flanges, means for keeping said rigid plate and said resilient 40 plate in lateral alignment, and means for laterally restraining a pad when held between said rigid plate and said flanges.

4. A holder for manifolding pad, comprising, in combination, a resilient plate, upturned webs at the ends of said resilient plate and flanges carried by said webs, a rigid plate embraced between said resilient plate and said flanges, said resilient plate 45 being adapted to urge said rigid plate into engagement with said flanges, means for keeping said rigid plate and said resilient plate in lateral alignment, a spring clamp carried by said web engaging one of said flanges for the retention of transfer sheet, 50 and means for laterally restraining a pad when held between said rigid plate and said flanges. 55

5. A holder for a manifolding pad comprising, in combination, a resilient plate 60 having upturned webs at its ends for confining a pad, flanges carried by said webs extending over the face of the pad but terminating short of the space intended for inscription whereby the central portion of 65 the face of the pad is exposed from one edge to the other, a rigid plate within said back member, and means for limiting the lateral movement of the pad in both directions, said back member being adapted to urge said pad 70 outwardly to bear against said flanges.

In testimony whereof I affix my signature.

EDWARD KIRBY BOTTLE.
